UNITED STATES PATENT OFFICE.

OLLYN A. LAYNE, OF LOS ANGELES, CALIFORNIA.

SEPARATOR FOR WELLS.

1,302,815.

Specification of Letters Patent.

Patented May 6, 1919.

Application filed September 17, 1917. Serial No. 191,677.

To all whom it may concern:

Be it known that I, OLLYN A. LAYNE, a citizen of the United States, residing at Los Angeles, in the county of Los Angeles, State 5 of California, have invented new and useful Improvements in Separators for Wells, of which the following is a specification.

This invention relates to devices for separating sand and liquid in wells, such as oil 10 and water wells, etc.; and relates particularly to pipe separators adapted to allow the entry of liquid and at the same time prevent entry of sand. It is a primary object of this invention to provide such a device which 15 may be efficiently and economically manufactured and which will act efficiently to perform its services.

Another object is to provide a separator of this character which may be formed (that 20 is, finally formed as a separator) by a certain method hereinafter explained, and particularly explained and claimed in my copending application entitled, Method of forming separators for wells, filed on November 13, 1916, 25 and bearing Serial No. 131,022. Other objects and features of the invention are made apparent in the following detailed specification wherein I describe preferred forms of my device. For the purpose of this description 30 I refer to the accompanying drawings in which—

Figure 1 is an elevation of one form of my device, parts being shown in section; Fig. 2 is a similar elevation of another form of 35 my device; Fig. 3 is a cross section of either of the forms shown in Figs. 1 and 2; Fig. 4 is an enlarged detail section taken as indicated by line 4—4 on Fig. 3; and Fig. 5 is a similar section showing the parts in the 40 position in which they are put into a well.

I have found by experience that sand, silt, etc., can be excluded from the interior of a perforated pipe if the perforations in the pipe are so protected that the sand, etc., must either flow upwardly or must flow substantially horizontally in order to reach the perforations. The fluid will of course flow upwardly beneath the protectors and then flow through the perforations; while the sand, etc., will not reach or flow through the perforations unless it is allowed to flow downwardly to and through the perforations at an angle sufficient to cause its flow. In an application copending herewith Serial Number 50 241,751, filed June 25, 1918, and which is in part a division of this present application I

explain a form of separator in which a nose-shaped protector entirely protects the opening against direct lateral flow of fluid, etc. In this present application I now explain 60 other forms of separators in which lateral flow (horizontal flow) of the fluid and sand, etc. is completely prohibited, or in which the angle of possible flow is substantially horizontal, so that the entrance of sand, etc. is 65 effectually shut off from the opening. It is a feature of the form which I herein explain that the protectors are arranged in the form of aprons, or the like, which extend entirely around the pipe or casing; one of the 70 forms including a series of circular aprons placed one above the other, and the other form including a continuous spiral apron which extends completely around and around the casing or pipe.

In Fig. 1 of the drawings I show a pipe or casing at 10 provided with perforations 11^a. These perforations may be of any suitable or convenient form, size or placement; I preferably show them here as being round 75 perforations, either drilled or punched and arranged in circumferential belts or zones around the pipe. Overhanging each one of these belts of perforations there is an apron 20. Each apron preferably, although not necessarily, comprises a pair of thicknesses 80 of sheet metal as illustrated at 21 and 22 (see Figs. 4 and 5 particularly). The upper edges of each of these metal sheets is secured as by welding, to the pipe 10; and the lower 85 part of each apron and longitudinally of the pipe so that the lower parts of the apron may be expanded in conical formation to the position illustrated in Figs. 1, 3 and 4. The slits in the two thicknesses of metal are 90 staggered so that the solid portions of one apron sheet will come opposite the slits of the other apron sheet and thus make an apron which is substantially impervious to sand, silt and the like. The slits are shown 95 at 23 in the drawings. The lower edge of the outermost apron sheet is provided with a slight hook or catch 25 which catches under the outer lower edge corner of the inner apron sheet when the aprons are expanded, 100 and thus prevents the aprons from springing back to position, or toward position, against the casing or pipe. In their expanded conical position each apron sheet covers the slits in the other, in a sort of shingling 105 effect; and their lower edges are below the lowermost holes or parts of the holes 11^a so

that in order to reach the holes 11^a it is necessary that any fluid must flow upwardly, under or behind the edge of the apron. Fluid such as water and oil will do this, but 5 sand and silt will not.

The form shown in Fig. 2 is substantially the same as that shown in Fig. 1 as hereinbefore described, excepting that the apertures or perforations 11^a are arranged in a 10 spiral belt around the pipe and the apron 20^a (constructed otherwise just the same as hereinbefore described) is arranged in a continuous spiral belt around the pipe covering the spiral belt of openings in the same 15 manner that the endless aprons of Fig. 1 cover the apertures of each belt.

In this form of device, direct horizontal flow of fluid or of sand, etc. to the apertures is also practically cut off because fluid, sand, 20 etc. must enter under the edge of the spiral apron in order to reach the apertures. Now, although it might appear from a theoretical consideration of the case, that a horizontal flow of fluid or of sand to the apertures is 25 possible, by a flow which would flow past and under the edge of the spiral protector at a point, say at the left in Fig. 2, horizontally around the course to the apertures 11^a at the right in Fig. 2, yet such a flow 30 does not take place in practice because this flow is not the shortest flow to the apertures. The shortest flow to the apertures is one which enters under the apron at a point opposite or nearly opposite the holes through 35 which the flow is taking place and then passes upwardly and inwardly to and through the holes. This is the line of shortest flow and also the line of least resistance to flow. The form shown in Fig. 2 is therefore 40 a very effective form of protector, and is, moreover, very simply and economically manufactured.

Both the forms shown in these drawings are designed to be placed in a well with the 45 aprons in position against the pipe as illustrated in Fig. 5. In such form the lower edge of each apron is designed to come close to or into contact with the upper edge of the next apron (or the lower edge of one course 50 of the spiral apron in Fig. 2 is designed to come close to or into contact with the upper edge of the next course below). So that when the aprons are flat against the pipe the whole pipe presents a smooth, cylindrical exterior surface and may be lowered in a well without any obstruction and without deforming the apron. When it is desired to form the separator into its operative form, then the aprons are moved outwardly, preferably by internal shock or 55 concussion or impact, such as may be delivered to the aprons through the medium of a liquid upon which an impact is delivered or to which a shock is delivered by the detonation of an explosive within the casing. 60

Such a method is the subject matter of my application S. N. 131,022 filed Nov. 13th, 1916. It will be understood however, that the separator is not necessarily limited to this particular method of formation. 70 Neither is the invention necessarily limited to other particular features of detail herein explained, except as specified by the following claims.

Having described a preferred form of my 75 invention, I claim:

1. A well pipe separator, embodying a pipe having a plurality of spaced openings through its walls, and a protector apron extending entirely around the pipe and hanging downwardly and outwardly over the openings in downwardly flaring form, said apron being attached to the pipe around its upper edge and being vertically slitted up from its lower edge. 80

2. A well pipe separator, embodying a pipe having a plurality of spaced openings through its walls, and a protector apron extending entirely around the pipe and hanging downwardly and outwardly over the 85 openings in downwardly flaring form, said protector apron being of double sheets of metal each slitted up from its lower edge and the slits in the two sheets being in staggered relation. 90

3. A well pipe separator, embodying a pipe having a plurality of spaced openings through its walls, and a protector apron extending entirely around the pipe and hanging downwardly and outwardly over the 95 openings in downwardly flaring form, said protector apron being of double sheets of metal each slitted up from its lower edge, and means on the slitted parts of one of the apron sheets engaging the slitted parts 100 of the other apron sheet to hold the two sheets in position. 105

4. A well pipe separator, embodying a pipe having a plurality of spaced openings through its walls, and a protector apron extending entirely around the pipe and hanging downwardly and outwardly over the 110 openings in downwardly flaring form, said protector apron being of double sheets of metal each slitted up from its lower edge 115 and the slits in the two sheets being in staggered relation, and means on the slitted parts of one of the apron sheets engaging the slitted parts of the other apron sheet to hold the two sheets in position. 120

5. A well pipe separator, embodying a pipe having a plurality of spaced openings arranged on a spiral line around the pipe walls, and a spiral protector member on the outside of the pipe over the openings. 125

6. A well pipe separator, embodying a pipe having a plurality of spaced openings arranged on a spiral line around the pipe walls, and a spiral protector apron on the outside of the pipe over the openings, hang- 130

ing downwardly and outwardly over the openings.

7. A well pipe separator, embodying a pipe having a plurality of spaced openings arranged on a spiral line around the pipe walls, and a spiral protector apron on the outside of the pipe over the openings, hanging downwardly and outwardly over the openings, said apron being attached to the pipe around its upper edge and being vertically slitted up from its lower edge.

8. A well pipe separator, embodying a pipe having a plurality of spaced openings arranged on a spiral line around the pipe walls, and a spiral protector apron on the outside of the pipe over the openings, the apron being of two sheets of metal one overlaid on the other, attached to the pipe at their upper edges and hanging downwardly and outwardly over the openings.

9. A well pipe separator, embodying a pipe having a plurality of spaced openings arranged on a spiral line around the pipe walls, and a spiral protector apron on the outside of the pipe over the openings, the apron being of two sheets of metal one overlaid on the other, attached to the pipe at their upper edges and hanging downwardly and outwardly over the openings, each apron

sheet being vertically slitted up from its lower edge and the slits in the two sheets being in staggered relation to each other.

10. A well pipe separator, embodying a pipe having apertures through its walls, and a protector member overhanging the apertures lying against the pipe at its upper edge above the apertures and being slitted up from its lower edge.

11. A well pipe separator, embodying a pipe having apertures through its walls, and a protector member overhanging the apertures lying against the pipe at its upper edge above the apertures and comprising two superimposed sheets each slitted up from its lower edge and the slits in the two sheets being in staggered relation so that the slits of one sheet are covered by the other sheet.

12. A well pipe separator, embodying a continuous integral well pipe with apertures through its walls, and a protector member overhanging the apertures and extending around the pipe, secured to the pipe at its upper edge and flaring outwardly and downwardly over the apertures.

OLLYN A. LAYNE.
